UNITED STATES PATENT OFFICE.

FRANK O. WOODLAND, OF WORCESTER, MASSACHUSETTS, ASSIGNOR TO ECONOMIC MACHINERY COMPANY, OF WORCESTER, MASSACHUSETTS, A CORPORATION OF WEST VIRGINIA.

LABELING-MACHINE.

1,113,855.

Specification of Letters Patent.

Patented Oct. 13, 1914.

Application filed January 13, 1913. Serial No. 741,624.

To all whom it may concern:

Be it known that I, FRANK O. WOODLAND, a citizen of the United States, residing at Worcester, in the county of Worcester and 5 State of Massachusetts, have invented new and useful Improvements in Labeling-Machines, of which the following is a specification, reference being made therein to the accompanying drawings.

10 My present invention relates to certain features of improvement in the construction and organization of the mechanism for delivering, gluing and presenting labels for affixment to bottles or the like, and more 15 especially applicable to that class of machines in which there is employed a rotatable work-supporting table or carrier.

It also relates to the peculiar manner of constructing, combining and operating the 20 label-gripping or clamping means in connection with the bottle-supporting carrier and label applying devices; the objects being to provide a practical, desirable labeling machine that will be convenient for operation, 25 and will perform its work with despatch and economic efficiency.

Minor objects and features of the invention are fully set forth and explained in the following detailed description, with reference 30 to the drawings, wherein—

Figure 1 represents a bottle labeling machine embodying the features of my invention. Fig. 2 is a view of the same looking toward the end of the picker-slide; the end 35 of the picker guide being shown in section; the discharger being omitted from this figure. Fig. 3 represents a top plan view. Fig. 4 is a plan view of the rotary carrier table and adjacent parts. Fig. 5 is a detached elevation view showing the bottle-rest, the label-gripping device and a bottle 40 as embraced between said parts. Figs. 6 and 7 represent the side and face views of the grip-member. Fig. 8 represents a top view, 45 and Fig. 9 a side view of one of the swinging grip-carrier arms. Fig. 10 represents a cross-section at line X X, Fig. 6, of the grip member drawn to a larger scale. Fig. 11 is a detail elevation view showing the improved 50 organization of the pickers and glue-supply mechanism. Fig. 12 represents a plan detail view of the picker devices, glue distributing rollers, and picker-carrier stop mechanism, and Fig. 13 shows a separate

sectional view of the picker-stop means on 55 larger scale.

Referring to the drawings, the part marked 10 represents the frame, preferably consisting of an upright column having a broad base for standing upon a floor; and fixed in 60 its upper end is a vertical shaft 1 (see dotted lines Fig. 2) upon which is mounted the rotatable table or carrier 12, having an upwardly extended hub provided at its top end with a dish-shaped bevel gear 2, or means 65 for its rotation, with which engages a pinion 3 fixed upon a horizontal shaft 5 that is arranged across said gear slightly above its rim, and mounted in bearings 4 supported upon suitable arms of the upper frame; said 70 upper frame being in the present instance supported by a main arm 11 fixed to and branching outward and upward from the side of the standard or column 10.

The shaft 5 is the operating shaft, and is 75 provided with a normally loose pulley or drive-wheel P, and an automatic stop-clutch C keyed to the shaft and adapted for operatively connecting and disconnecting said pulley or drive-wheel with said shaft. The 80 clutch is arranged for control by a treadle T and connections t, substantially as is usual in machines of this class. The action imparted to the machine may be intermittent or continuous, accordingly as the clutch is allowed to automatically throw off, or is prevented from throwing off, by keeping the treadle depressed.

The revolute carrier 12 is provided with a series of upright rests or means 13 for supporting the bottles B, or the like, in upright position, to be advanced or carried in a circular path of movement as the table 12 is rotated, carrying the bottles in successive order to positions for receiving their labels, 85 passing the wipers, and thence to the place of discharge, as will readily be understood.

The rest 13 is preferably made narrow at its lower part and wider above, and with a simple rearwardly offset foot or ear that has 100 a hole therein for bolting it to the carrier table. The wider portion of the rest forms a seat for the bottle, while the narrower lower portion avoids interference with the wipers as the rest passes between them. The 105 rest gives support at about mid-height on the bottle.

In accordance with my present invention,

there is arranged a guide bar or way 14 disposed parallel with the plane of the carrier 12, and in alignment with a plane approximately tangential to the circular path of the 5 moving bottles. Upon said guide is mounted a reciprocating picker-carrying slide 16, to one end of which the glue-applying pickers or plates 6 are rigidly attached; said pickers being disposed in a depending relation, with 10 their faces nearly perpendicular to the slide, or slightly inclined from a vertical position, the inclination being of a degree to conform to and accommodate the difference in diameter of the body and neck portion of the 15 bottles. The picker faces are toward the label-supply holder 15, and for reciprocating the picker-slide 16 along the guide 14 there is provided means which, in the present instance, consists of a rocker or angle 20 lever 17 supported in a suitable fulcrum bearing 7 upon the frame, and having one arm connected by a suitable link 18 with the slide 16 and a second arm provided with a stud-roller 8 that runs upon or follows the surface 25 face of a cam 9 fixed upon the operating shaft 5. A suitable spring S is connected with the rocker lever 17 for moving the parts to carry the pickers toward the label-holder and normally pressing the stud-roller toward 30 the cam 9.

The reciprocation of the slide carries the pickers 6 from the position of the label-holder 15 to the position indicated by a dot-and-dash line f (see Fig. 1) where the label 35 is presented to the advancing bottle as the latter moves forward with the rotary action of the carrier. The label-holder 15 is positioned at the end of the range to which the pickers reciprocate; the label compartments 40 being disposed edgewise upright or slightly inclined, to conform to the face of the pickers. The compartment for neck labels I is located above that for body labels L. The label holder is arranged to have the packs of 45 labels charged into it from the rear and to deliver the labels from that part of the packs toward the pickers. A follower device is provided for the several packs, which preferably consists of a movable rest or 50 inverted Y-shaped frame 19 arranged to slide upon a guide, or guides, 20 parallel with the direction of the feed, and having, retained in said frame, the follower rods 21 that abut against the respective packs, as 55 indicated on Figs. 1 and 3. A spring 22, arranged on the follower rod, serves to give a slight yielding effect when pressure of the pickers is brought against the label-pack, and a weight 23, suitably attached to the 60 sliding frame 19, serves for moving the follower devices forward along the guide pins 20 as the packs are diminished by the feed. To facilitate charging the packs of labels into the rear of the compartments, the frame 65 19 is simply drawn back along the guide

pins 20 to a sufficient extent to permit access to the compartments.

The label holder is best arranged to be bodily removable from its supporting seat or bracket, and may be connected therewith 70 by suitable pins or interlocking members such as heretofore employed for similar purpose.

The label-gripping devices, which co-act with the pickers in transferring the label 75 from the pickers to the bottle, according to my present invention are constructed and combined with the rotary bottle-carrier in peculiar manner and to swing laterally into and from the path of the bottles, each on a 80 pivotal axis parallel with the axis of said carrier. The gripping devices correspond in number with the bottle stations or rests 13 upon the carrier-table. Each grip device 85 comprises a horizontally swinging arm or lever 24 pivotally connected to and located beneath the rotary carrier or table 12, by an axis pin or stud 26 disposed parallel with the main axis 1 of the carrier; and an upwardly extended bar or finger member 25 90 attached to the outer end of said swinging arm and projecting up through an opening or arc-shaped slot 27 in the carrier-table, to a sufficient height to correspond with the height at which the labels are placed; its 95 projecting portion standing approximately upright, and furnished with suitable contact surfaces or pads 28 and 29, (see Figs. 6, 7 and 10) to give proper hold upon the labels, surface 28 upon the neck labels and surface 100 29 upon the body labels. The end of the arm 24 is best made with a socket or recessed upright slot, and a screw bolt 30 arranged therein, while the lower end 31 of the grip-bar 25 is slotted or furcated and 105 fitted to said slot so as to be readily attached and detached, and to afford a firm and rigid connection. This construction permits of the bars or gripping fingers being readily exchanged for others of varied form, to accommodate longer or shorter bottles, or articles requiring different forms of grip faces.

Each of the swinging grip-carrier levers 24 has a projecting member provided with a stud-roller 32, and a suitably shaped stationary cam 33 is centrally supported upon the frame or standard 10 for guiding said rollers and controlling the swinging action of the gripping devices. Springs 34 are connected with the respective arms 24, that 115 act in opposition to the cam surface, for swinging the gripping devices in the direction for contact with the labels or bottle; the cam acting to swing the gripping devices 120 back to primary position. The upper part of the bar 24, with the contact faces, is the only portion of the gripping devices that appear above the level of the carrier table as they move in a circular arc into the path of the bottles, and then out of said path and 130

back to their retracted position near the central hub of said rotary carrier with which they also revolve.

5 A wiper mechanism 35 is arranged for acting against the advancing bottle and label at a convenient position, in successive relation to the pickers. Said wipers may be of any approved construction, being arranged so that the bottle, grip-member and bottle-
10 sustaining rest pass between the opposite wiping members by the rotative movement of the carrier.

15 The glue-box 37 is located below the path of the pickers, and near the label-holder 15, and is provided with a glue-delivery roller 38 which may be rotated by any suitable means, as the chain and sprockets 39. The glue distributing roller 40 is mounted upon an axis-stud fixed to an upwardly and down-
20 wardly reciprocating carrier 42 that works in a suitable guide 43 attached to the frame. Said carrier and roller move in a direction of alinement approximately parallel with the upright or slightly inclined plane of the
25 picker faces.

30 The range of movement of the distributing roller is from a position in contact with the glue-box roll 38, (see Figs. 1 and 11) to a position above the level of the top end of the picker faces, as indicated by dotted circles on Fig. 11; this movement being direct from its upper to its lower position and vice versa. Movement is imparted to the roller-carrier
35 42 by a rocker-lever 45 and link; said rocker being actuated by a cam 46 fixed on the operating shaft 5, which cam runs against a stud-roll 44 mounted on one arm of the rocker. The weight of the roller and its carrier tends to keep the stud-roll in contact
40 with the face of the cam; or a spring may be employed in connection therewith, if desired.

45 The mechanism or cam 9, which actuates the reciprocating picker-slide, is arranged to give a dwell in the picker movement when the picker faces are at the position indicated in Fig. 11, and for an instant sufficient to permit the glue-distributing roller to pass down from its upper to its lower position along the faces of the pickers, applying the
50 film of glue thereto just before the pickers come into contact with the pack, or packs, of labels.

55 Combined with the reciprocating picker-slide 16 I provide means for automatically arresting its movement before the pickers reach the label-holder or position of contact with the pack of labels. This stop mechanism comprises a bolt or dog 48 mounted in a guide or supporter fixed to a stationary
60 part of the frame, and provided with a spring 49 or means for throwing said dog into engagement with a suitable lug or shoulder 50 on the picker-slide 16, thereby preventing movement of said slide beyond a
65 predetermined position; excepting when the

dog is retracted. Said dog is connected with the swinging bottle-feeler 55 by an angle lever 53, rod 52 and arm 54 at the top of the feeler-shaft 56. When a bottle or the like is in position for receiving its label the feeler is pressed back to the position indicated in full lines on Fig. 3, and the dog is thereby retracted, permitting a full movement of the picker-slide; but when a bottle is absent from its station upon the rotating carrier then the feeler can swing forward allowing the dog to be projected by its spring into engagement, and the movement of the picker-slide is thereby arrested before reaching its normal limit of its action. The stop device is preferably arranged to effect its operation at a position corresponding with the dwell in the movement of the picker-slide, so that the stop-dog comes into action without shock or violent contact in the operation of the reciprocating action and without undue friction in moving the dog into and out of engagement. When the movement of the picker-slide is arrested any strain on the mechanism is relieved by the
70 roller 8 lifting from the face of the cam 9.

75 Combined with the rotary carrier 12 and its bottle-supporting rests 13, I employ a means for automatically discharging the bottles, which consists of a plain stationary fender or deflector-sheet 60 that extends over the top surface of the carrier obliquely across the path of the bottles, at a predetermined position in the circuit, and serves for shunting the bottle from the rest and deflecting it from the carrier table onto a supplemental table 61 or other receiver therefor. Said deflector is simply formed from a plain sheet of material and provided with an opening or pass-way space 62 at its lower edge, of
80 sufficient size to permit the passage therethrough of the bottle-rest 13, which is made narrow at its foot and wider above, as indicated. The deflector acts upon the bottle to shunt it from the rest and does not interfere
85 with the upright bottle-sustaining rest. This form of discharger is simple, convenient and efficient for use in a rotary labeling mechanism.

90 In the operation, the bottles or articles to be labeled are placed upon the carrier 12 at the front of the respective rests 13, and are thereby advanced in a circular path in successive order. The reciprocating picker-slide brings the pickers, with a label or
95 labels adhering thereto, to meet the advancing bottle at about the line f, Fig. 1; where, at the same time, the grip-bar or f, Fig. 25, swinging along its arc slot, comes into contact with the central part of the label and holds it to the bottle while the pickers move back at accelerated speed, causing the glued ends of the label to peel from the picker-faces. The bottle, moving with the carrier, then passes between the wipers 35 which
100

wipe or smooth the glued edges of the table to the surface upon which it is affixed; and thence to the discharge. In the meantime the reciprocating picker-slide brings the 5 pickers to the position of the glue-distributing roll and then dwells for a moment of time while the said roll, which has been previously elevated, rolls down along the picker-faces; the pickers are then advanced against 10 the packs of labels on the label-holder, taking single labels adhesively therefrom, and the operation is then repeated. This general operation, in its order of feeding and affixing labels is, in some respects, similar to 15 that of a previously devised labeling machine; but the construction and combined organization of the elements for performing the several essential functions is of diverse nature from that heretofore employed, and 20 constitutes the gist of my present invention.

I am aware that in practising this invention, some changes and modifications may be made, by those skilled in the art, without departure from the spirit and scope of my 25 invention as expressed in the claims; I do not, therefore, desire to be limited to the special forms and details as shown herein:

What I claim and desire to secure by Letters Patent, is—

30 1. In a labeling machine, in combination with label-delivering and label-affixing means, a horizontally rotatable carrier having means at intervals thereon for supporting bottles in upright position and carrying 35 the same in a circular path, means for actuating said rotatable carrier, a picker-guide disposed above said path at one side of the circle, a reciprocating picker-carrier-slide mounted upon said guide, a pair of glue-ap- 40 plying pickers firmly secured to said slide in a relatively depending position and traveling between said guide and the plane of the bottle-carrier, and means for imparting reciprocative movement to said picker- 45 slide.

2. In a labeling machine, in combination, a rotary bottle-carrier provided with means for supporting bottles in upright position thereon, and carrying the same in a circular path, a reciprocating picker-carrier-slide, a guide therefor arranged over one edge of said bottle-carrier approximately tangential to the path of the bottles, depending pickers mounted on said picker-carrying-slide, 55 a rear-charged forward-delivery label-holder adapted for sustaining packs of labels in edgewise upright order and disposed in alinement with the path of said pickers, a carrier-operating shaft, a cam mounted on 60 said shaft, and connections for actuating said picker-carrier-slide; said cam formed to produce a dwell in the picker movement when near the label-holder.

3. In combination, a horizontally rotatable carrier, provided with means for sustain-

ing bottles or the like in upright position thereon and moving the same in a circular path; a reciprocating picker-carrier-slide, depending glue-applying pickers mounted upon said slide, a guide for said picker-carrier-slide arranged substantially tangential to the circular path of the bottles and approximately parallel with the plane of the rotatable carrier, a label-supply holder adapted for holding a pack of labels in approximately edgewise upright position, at the end of the reciprocating picker movement, an upwardly and downwardly moving glue-distributing roller, means for reciprocating said picker-carrier-slide, and means 75 for operating said glue-distributing roller; a grip mechanism, and wiper appliances for affixing the label to the bottle or the like.

4. In a labeling machine, a rotatable carrier table, having devices thereon for supporting a succession of bottles in upright order and carrying the same in a circular path, and label-gripping devices moving with said carrier; a reciprocating picker-carrying-slide, a pair of glue-applying 85 picker-plates attached to said slide approximately in transverse dependent relation, a guide-way upon which said picker-slide is mounted to move parallel to the plane of said bottle-carrier and in convenient with the 90 circular path of the bottles thereon, a label-supply holder in alinement with the path of said pickers, a glue-distributing roller, an upward and downwardly moving carrier for said roller, a guide therefor, means for 95 reciprocating said roller-carrier and said picker-carrying-slide, a wiping-on means, and a grip-controlling mechanism acting beneath the carrier-table.

5. In a labeling machine, in combination, 105 a rotary bottle-carrier provided with means for supporting bottles in upright position thereon, and carrying the same in a circular path, a reciprocating picker-carrying-slide, a guide therefor arranged above one edge 110 of said bottle-carrier in approximately tangential relation to the path of the bottles, depending pickers mounted on said picker-carrying slide, a rear-charged forward-delivery label-holder adapted for sustaining 115 packs of labels in edgewise upright order, and in deliverable alinement with the path of said pickers, a carrier-operating shaft, a cam fixed on said shaft, and connections for actuating said picker-carrier slide, said cam formed to produce a dwell in the picker movement when near the label-holder, a glue-supply reservoir, a glue-distributing roll, an upwardly and downwardly reciprocating carrier having said roll mounted thereon, an upright guide for said roll-carrier, a cam on said operating-shaft, with connections for elevating and depressing said roll-carrier, the downward reciprocative movement of said roll-carrier being 125 130

timed for occurring approximately coincident with the dwell in the picker movement.

6. In a labeling machine of the class described, in combination with means for gluing and presenting labels, means for wiping on the labels, and a rotatable bottle-carrier table; a movable label-gripping member above said carrier-table and traversing within a slot formed therethrough, means acting below the carrier-table for supporting and controlling said gripping member, a spring connected for moving said gripping member toward the bottle to impart a yielding-pressure grip upon the label, and means for rotating said carrier-table and gripping member.

7. In a machine of the class described, in combination with the rotary carrier, upright bottle-supporters thereon, glue-applying pickers, and means for affixing labels; a label-gripping means consisting of an upstanding member, the upper part having a pad or surface for contact with the bottle and label above the carrier, its lower end rigidly attached to a swinging arm, said swinging arm pivotally supported upon the under side of the rotary carrier to revolve therewith and to oscillate in a plane parallel with the plane of the carrier, for swinging said upstanding member into and from the path of the bottle, means for actuating said carrier, and means including a cam and spring for oscillating said grip-actuating arm.

8. In a labeling machine, a rotary carrier provided with rests for the upright support and advancement of a succession of bottles or the like in a circular path, a label gripping means consisting of an upstanding bar or grip-member having contact surfaces, and a swinging support therefor to which the lower end of said grip-member is detachably firmly secured, said support pivotally connected with the rotary carrier, and said grip-member projecting up through an arc slot in the carrier, in combination with a picker-carrier, glue-applying pickers thereon, means for gluing the pickers, and means for affixing the labels.

9. In a labeling machine, in combination with a label supply, means for delivering labels at a predetermined position for transfer to a bottle, and means for wiping on said labels at a second predetermined position, a horizontally rotatable carrier table provided with means for supporting a bottle or the like in upright relation thereon, and advancing the same, an upright laterally moving grip-device traversing in a curved slot in the carrier-table, its lower end below the table, a horizontally swinging lever having said grip-device mounted thereon, a fulcrum stud fixed in the under side of the carrier for supporting said lever, a spring attached for normally swinging said lever outward, a

traversing roll mounted on said lever, and a non-rotatable guiding means about which said roll travels for actuating and controlling the movement of said grip-device.

10. In a labeling machine, a label supply, means for delivering labels for affixment to an advancing bottle, and retreating therefrom by retroactive movement at greater velocity than the bottle movement, a separately stationed wiper-means for affixing said labels, a rotary bottle-carrier provided with a series of upright bottle-rests, and a corresponding series of laterally moving upright label-gripping devices that traverse to a position in front of the bottle and against the presented label, maintaining such relation while passing said wiper-means, then back to a position nearer the axis of the carrier, for the purpose set forth.

11. In a labeling machine of the class described, a rotary bottle-carrier provided with bottle-rests, said rests being adapted to contact with the bottles at a mid-length position thereon, and upright oppositely acting label-gripping devices having faces that contact with the labels and bottle respectively above and below the level of the contact position of said rests and means for wiping on the respective labels.

12. In a labeling machine of the class described, a rotatable carrier provided with a plurality of rests for bottles or the like, and a plurality of grip-devices each consisting of an uprightly disposed bar having a contact face for pressing upon the label, said bar projecting up through an opening or arc slot in the carrier, to move therein laterally into and from the path of said rests, and a plurality of swinging supporters acting beneath the carrier table and supporting the respective grip-bars, means for actuating and controlling the movement of said supporters and grip-bars and means for affixing the labels upon the advancing bottles.

13. In a labeling machine of the class described, in combination with means for gluing, presenting, and affixing labels, a horizontally rotating carrier-table having a series of arc slots therethrough, and provided with a series of upright rests for sustaining bottles or the like thereon while labeling the same; a series of swinging arms pivoted to and located beneath said table concentric with the respective arc slots and carrying at their outer ends upright grip-bars or fingers that project upward through said arc slots, said grip-bars being movable within their slots to and from the positions of the bottles for gripping the presented labels above the carrier, and means for imparting swinging movement to said grip-carrying arms as the carrier is rotated.

14. In combination with glue-applying pickers, a label-holder and label wiping devices; a horizontally rotatable carrier hav-

- 6
15. ing means thereon for maintaining in successive order a series of bottles or the like while affixing labels thereto, a plurality of pivoted support-arms fulcrumed to the under side of said rotatable carrier, each provided at its end with a grip-device that projects upward through an arc-shaped slot in the carrier, the opposite ends of said support arms being provided with contact rollers, a stationary central cam against which said rollers run for controlling the movement of said grip-devices, and each arm being provided with a spring for pressing the grip device into contact with the label and bottles.
20. 15. In a labeling machine for bottles or the like, in combination with a bottle-carrier and means for affixing labels, a label-holder adapted for supporting packs of labels in approximately edge-wise upright position for forward delivery of labels therefrom, a horizontally reciprocating picker-slide, pickers carried by said slide in a depending relation with their faces parallel with the label pack, and said picker-slide and pickers movable to and from said label-holder, and a follower for said label packs, comprising a slidable supporting rest or member, guides therefor approximately parallel with the direction of the label-packs, follower-rods movably supported within said member and respectively abutting against the label packs, a forwardly pressing spring for each of said follower-rods, and a weight and connection adapted for exerting forward draft upon said supporting rest.
25. 16. In a machine for labeling bottles or the like, the combination substantially as described, of a label-holder adapted for supporting a pack of labels in approximately edge-wise upright position for forward delivery of labels therefrom, an overhead horizontal guide, a reciprocating picker-slide mounted thereon, pickers supported by said slide in a depending relation with their faces parallel with the label pack, an upwardly and downwardly moving gluing distributing roller, a carrier and carrier-guide for directing said roller parallel with the face of the pickers, a horizontally rotatable bottle-carrier, means thereon for sustaining bottles in upright position and advancing the same in a circular path convenient with the line of the picker movement, a horizontally swinging grip device, a grip-supporting arm pivotally mounted on the under side of said rotary carrier, means for controlling and moving said supporting arm, label wipers between which the bottle is passed by its carrier, means for actuating said reciprocating parts, and means for operating said rotatable carrier.
30. 17. In a labeling machine, in combination as described, a rotary bottle-carrier table having rests thereon for maintaining bottles or the like in upright position, means for
35. 18. In a labeling machine, including a label-supply holder, means for advancing bottles in successive order, and a picker-carrier and pickers having reciprocating movement between said label-holder and the advancing bottle, and meeting the bottle at a predetermined position for presenting labels thereto; an automatically controlled means for arresting the movement of the picker-carrier and pickers while approaching the label-holder, and actuating means therefor operating when a bottle is absent from its advancing station.
40. 19. In a labeling machine, in combination with means for supplying labels, and means for affixing the labels; a movable bottle-carrier provided with rests for sustaining bottles upright thereon and carrying forward the same in successive order, a pair of glue-applying pickers movable to and from the advancing bottle and traveling in a path convergent to the path of the bottles and carrier for presenting or delivering labels thereto approximately at the point of convergence of said paths; grip-devices traversing in curved slots in the carrier and severally adapted to retain the label against the bottle and strip it from the glued faces of the pickers while said grip-device, bottle, and pickers are all moving away from the position where the label is primarily presented to the advancing bottle, and means for operating said grip-devices severally synchronous with the presentation of labels.
45. 20. In a labeling machine, a movable bottle-carrier having means for carrying forward or advancing a succession of approximately upright bottles, and a reciprocating picker-carrier provided with pickers in approximately transverse relation thereto, directing guides upon which said picker-carrier slides, and means for operating said picker-carrier for moving the pickers into meeting conjunction with the advancing bottles and retreating in the direction of the bottle movement, at accelerated speed, in combination with means for supplying and affixing the labels.
50. 21. In a labeling machine, a rotary bottle-carrier, an upright laterally moving label-grip-member that travels in a circular arc, said member having means for contact with neck labels and body labels, and a grip-member supporter located beneath and ful-

crummed on said bottle-carrier, and means for operating the same.

22. In a labeling machine, in combination with means for supporting and successively carrying forward bottles, and means for wiping the labels; of a label supply-holder, a movable picker-carrier having pickers thereon that take labels from said label-holder, means for automatically arresting the movement of said picker-carrier before the pickers contact with the label-supply, and a controlling finger with connections that prevent action of said arresting means when a bottle is in proper position for receiving its label.

23. In a labeling machine, a rotary table carrier having slots therein, means for sustaining bottles or the like upon said table in suitable relation to said slots, grip-devices above the table traversing in the respective slots, and means below the table for operating said grip-devices.

24. In a labeling machine, in combination, a forwardly moving bottle-carrier provided with a plurality of bottle-carrying devices 25 positioned thereon, a backwardly and forwardly moving label-presenting means that presents labels to the bottles at a predetermined position on said carrier, and a laterally moving grip device that travels with 30 said carrier and acts for withdrawing the labels from the presenting means at its junction with the bottles, said label-presenting means being retracted at a velocity greater than the advance motion of the bottle 35 carrier, mechanism for respectively operating said carrier, label-presenting means and gripping-device.

Witness my hand this 10th day of January, 1913.

FRANK O. WOODLAND.
